RAIL BOND TERMINAL

Harold H. Febrey, South Orange, N. J., assignor
to The American Steel and Wire Company of
New Jersey, a corporation of New Jersey

Application May 14, 1940, Serial No. 335,181

5 Claims. (Cl. 238—14.13)

This invention relates to rail bond stud terminals of the type adapted for installation by way of bottomed rail holes or recesses, and is particularly concerned with signal bond stud terminals of the type installed in bottomed holes or recesses formed in the sides of the rail heads.

Railroads now commonly specify that the holes formed in the sides of the rail heads for effecting installation of this type of stud terminal signal bond, have a diameter of $\frac{3}{8}$ of an inch and a depth of $\frac{1}{4}$ of an inch. The dimensions of these holes vary slightly according to the condition of the drill used to form them and the manipulation of this drill.

The problem of providing stud terminals for installation by way of these small holes has been met by various designs, the one with which the present invention is concerned being that wherein in a hole is formed through the terminal head and into the stud, the hole opening from the side of the head opposite the stud and a malleable metal insert being positioned in the hole within the stud. Installation is effected by means of a tool which a workman positions in the hole through its opening so as to contact the insert, the tool then being struck a few blows with a hammer by the workman so as to compress the insert and expand the same, this effecting expansion of the stud against the rail metal surrounding the hole. There are variations in the design of this terminal but the principles involved are broadly as just described.

The tool used by the workman is in the form of a punch and its working end must be of sufficient size to prevent its breaking when stressed by the hammer blows. A $\frac{1}{4}$ inch diameter cylindrical end is now generally considered a standard. Since the rail hole is only $\frac{3}{8}$ of an inch in diameter and experience has shown that the working end of the tool cannot safely be reduced to a diameter less than this standard, it follows that the wall of the stud surrounding the insert on which this tool works is relatively thin.

It is necessary to remove rail bonds on occasion, and the terminal design under discussion has the disadvantage in that its necessarily thin wall has a maximum tensile strength of only about 2600 pounds, while its frictional hold in the rail hole varies over a range of from 2000 pounds to as much as 4000 pounds depending on how efficiently it was installed, it following that the removal of bonds having terminals of this design frequently involves breaking off the studs in the holes. When this happens, the usefulness of the bond is destroyed in case its specific termi-

nal design permits its reuse and it is necessary to drill out the stud remains from the rail hole, this being an expensive and troublesome procedure and involving the danger of undue enlargement of the rail hole.

Keeping the foregoing in mind, a signal bond terminal constructed in accordance with the present invention but following the general design discussed, has the advantage that it permits the use of a punch having a full-size working end, this being the standard $\frac{1}{4}$ inch round cross section, while at the same time providing a stud having a wall that is thickened to provide the stud with a tensile strength exceeding the holding strength of the stud in the rail hole. This desirable effect is attained entirely without a decrease in the normal holding strength of the stud in the rail hole.

For instance, the invention permits the provision of a terminal made of the usual soft steel having a tensile strength of around 53,000 pounds per square inch, with its stud wall sufficiently thick to provide the stud with a tensile strength considerably exceeding 4000 pounds, the holding power of the stud in the rail hole ranging above 2000 pounds although, of course, it does not exceed the maximum holding power of this design of terminal when constructed according to the prior art.

The accompanying drawing illustrates signal bond terminals of the design under consideration and which embody the invention, the various figures being as follows:

Figure 1, a longitudinal section of a first example inserted in a rail head hole and ready for installation by the standard punch;

Figure 2, an end view of this terminal with the punch removed; and

Figure 3, a view similar to Figure 1 excepting that it shows a modification and the standard punch is not used, this punch being substituted by a tool carried by the terminal itself. No end view of this modification is shown since it would look the same as Figure 2.

More specifically, both examples are conventional insofar as they include a head 1 and a stud 2, the latter being externally dimensioned to fit a hole formed in the side of a rail head when this hole is of the dimensions now commonly specified by the railroads. The punch 3 is also conventional in that its working end is of a $\frac{1}{4}$ inch round cross section. It might be mentioned that this punch 3 is usually provided with a handle 55 for positioning it and has a head opposite its

working end, which is struck by the workman with a hammer.

The terminal is novel in that the hole opening from the side of the head 1 opposite the stud 2 and extending through the head and into the stud almost to the end of the latter, is made with a portion 4 within the head and including the hole opening, which is of standard diameter, whereas the remainder 5 of the hole including all of that within the stud and a part within the head, has a reduced diameter. This construction provides the stud including its junction with the head, with a wall that is much thicker than standard. For example, assuming the stud to have a diameter of slightly less than $\frac{3}{8}$ of an inch, and the hole within this stud to be about $\frac{1}{8}$ of an inch, the stud is provided with the higher tensile strength previously described when made of steel having that tensile strength.

Expansion of the stud is effected by a malleable metal insert 6, this insert extending from the bottom of the hole and up into the full-size portion 4 of the hole within the head. It follows that its expansion may be effected in the usual manner by the use of the usual tool, yet the tensile strength of the stud exceeds its maximum possible holding power in the rail hole, whereby the terminal can always be removed without fear of fracturing its stud.

The insert 6, made of copper, is shown as filling the portion 5 of the hole within the stud and as being cylindrical throughout its length including its portion extending into the standard size portion 4 of the hole. Therefore, when the tool 3 is struck with the first blow of the hammer, the first action is to flatten out the end of the insert. The flattened metal upsets onto an annular shoulder 7 at the junction between the portions 4 and 5 of the hole, this shoulder being made sufficiently abrupt so that a part of the force of the first hammer blow and the force of succeeding blows is transmitted longitudinally through the upset insert metal into the shoulder and so through the head into the thick stud wall, it being understood that a large portion of the force of the hammer blows goes into longitudinal compression of the insert so as to effect its lateral expansion with consequent expansion of the stud.

One difficulty experienced with terminals of the design here involved, is the tendency of the terminal stud to retreat from the rail hole while being expanded by the insert. However, in the case of the present terminal, this tendency is entirely counteracted by the fact that a portion of the insert expanding force is transmitted longitudinally into the stud wall so as to prevent the stud from retreating from the rail hole. At the same time, this force transmitted into the stud wall tends to shorten the stud wall which by itself results in expansion of the stud through thickening of its wall which, at the same time, is being expanded by the expanding insert.

In the case of the modified terminal illustrated by Figure 3, the same parts are used and are therefore similarly numeraled excepting that the letter a is used for identification purposes. The punch 3 a is in the form of a tool included by the terminal as a part of the same. This tool may be retained in the hole portion 4 by being press-fitted into place, it being understood that while it is not necessary that this tool be so sturdy as when the removable punch is used which must effect the installation of a large

number of bonds, it is still desirable to have it as strong as it can possibly be made. In other words, a terminal of the type having the tool built into it is useless if the tool fails after the first one or two hammer blows or when the terminal is reused.

Another difference in this modification is that the insert 6 a has its end flattened at the time of the manufacture of the terminal so that it 10 completely fills the portion 4 a of the hole that is of standard size. By preflattening or upsetting this end, the first hammer blow transmits the same portion of its force longitudinally into the stud wall as do subsequent blows. 15 This feature may also be incorporated when the tool used is of the type shown in the case of the first example, it being necessary to consider the tool as part of the terminal in all instances, because one of the primary advantages of the present invention is its ability to use the standard working end of the usual punch.

I claim:

1. A rail bond terminal having a head and a stud with a hole opening from the side of the head opposite the stud and extending through the head and into the stud, the hole terminating inside the stud and the portion of the hole within the stud having a smaller diameter than a portion of the hole within the head including the opening to the hole, and a malleable insert positioned in the first named portion of the hole with an end extending towards the second named portion of the hole.

2. A rail bond terminal having a head and a stud with a hole opening from the side of the head opposite the stud and extending through the head and into the stud, the hole terminating inside the stud and the portion of the hole within the stud having a smaller diameter than a portion of the hole within the head including the opening to the hole, and a malleable insert positioned in the first named portion of the hole with an end extending towards the second named portion of the hole, the diameter of the 45 first named portion of the hole being sufficiently small as compared to the outside diameter of the stud to provide the latter with a wall thickness furnishing the tensile strength necessary to permit forcible withdrawal of the stud without 50 its fracturing when it is installed in a rail hole by expansion of the insert so as to provide the stud with its maximum holding strength in the rail hole, and the diameter of the second named portion of the hole being sufficiently large as 55 compared to the outside diameter of the stud so as to permit the insertion of a tool end of a diameter so great that if the first named portion of the hole were of sufficient diameter to permit insertion of the same tool end, the wall 60 thickness of the stud would not furnish the tensile strength here defined.

3. A rail bond terminal having a head and a stud with a hole opening from the side of the head opposite the stud and extending through the head and into the stud, the hole terminating inside the stud and the portion of the hole within the stud having a smaller diameter than a portion of the hole within the head including the opening to the hole, and a malleable 70 insert positioned in the first named portion of the hole with an end extending into the second named portion of the hole, the junction between the two portions of the hole being in the form of an annular shoulder adapted to receive metal 75 upset from the insert when the latter is com-

pressed by a compression tool and to transmit some of the compression force exerted by the tool longitudinally into the stud.

4. A rail bond terminal having a head and a stud with a hole opening from the side of the head opposite the stud and extending through the head and into the stud, the hole terminating inside the stud and the portion of the hole within the stud having a smaller diameter than a portion of the hole within the head including the opening to the hole, and a malleable insert positioned in the first named portion of the hole with an end extending towards the second named portion of the hole, the terminal including a tool of a diameter larger than the first named portion of the hole fitted in the second named portion with an inner end contacting the insert and an outer end projecting through the opening to the hole beyond the side of the head opposite the stud.

5. The combination of a railroad rail head having a hole formed in its side of the dimen-

sions used to provide for the installation of a signal bond of the stud terminal type, and a signal bond terminal having a head and a stud inserted in said hole with a hole opening from the side of the terminal head and extending through the latter and into the stud, a malleable metal insert being expanded in the portion of the terminal hole within the stud and the latter being expanded thereby so it holds in the rail hole, the portion of the terminal hole within the stud being of such a small diameter that the stud wall is sufficiently thick to have a tensile strength exceeding the strength of its hold in the rail hole, the insert terminating within the terminal head and the portion of the terminal hole between the insert end and the terminal hole opening being sufficiently large to accommodate the entrance of the working end of the type of punch used to install signal bonds of the type here defined when this working end is of standard size.

HAROLD H. FEBREY.
